UNITED STATES PATENT OFFICE.

FRANKLIN S. MCKENNEY, OF DETROIT, ASSIGNOR OF ONE-HALF TO J. M. LONGYEAR, OF MARQUETTE, MICHIGAN.

DESIGN FOR A FASTENER.

SPECIFICATION forming part of Design No. 25,138, dated February 11, 1896.

Application filed December 9, 1895. Serial No. 571,593. Term of patent 14 years.

To all whom it may concern:

Be it known that I, FRANKLIN S. MCKENNEY, a citizen of the United States, residing at Detroit, county of Wayne, State of Michigan, have invented and produced a new and original design for a Fastening, of which the following is a full, clear, and exact description, reference being had to the accompanying drawings, which form a part of this specification.

In the drawings, Figure 1 is a view in perspective showing my fastening with prongs projecting upward from the head. Fig. 2 is a plan view looking toward the points. Fig. 3 is a reverse plan view.

My fastening comprises as its leading features a head A and prongs *a a* projecting at essentially right angles therefrom. The main

portion of the head is shaped with the portions of the head adjacent to the base of the prongs curved or coiled inward toward the center of the fastening. The central or middle portion of the head projects laterally between the bases of the prongs, as shown. A border or marginal flange surrounds the bases of the prongs.

What I claim is—

The design for a fastening substantially as herein shown and described.

In testimony whereof I sign this specification in the presence of two witnesses.

FRANKLIN S. MCKENNEY.
